UNITED STATES PATENT OFFICE.

MARTIN V. HAMMACK, OF THALIA, VIRGINIA, ASSIGNOR OF ONE-HALF TO
CEPHUS O. GRIMES, OF PORTSMOUTH, VIRGINIA.

DESIGN FOR A BUREAU OR SIMILAR ARTICLE.

SPECIFICATION forming part of Design No. 35,948, dated June 10, 1902.

Application filed February 14, 1902. Serial No. 94,124. Term of patent 14 years.

To all whom it may concern:

Be it known that I, MARTIN V. HAMMACK, a citizen of the United States, residing at Thalia, in the county of Princess Anne and State of Virginia, have invented and produced a certain new and useful Design for a Bureau or Similar Article, of which the following is a specification.

My said invention consists in a design for a bureau or dresser, whereby a very attractive and ornamental piece of furniture of such character is provided.

The accompanying drawing, on which similar letters of reference indicate similar parts, illustrates the front elevation of a bureau of my design.

Said design has a star for its leading characteristic. The mirror-surface M is in the form of a star. The lower portion has a door D, the front of which is ornamented with a star. On each side is a row of small drawers, the front of each of which is likewise ornamented by a star F.

On the top of the mirror-frame I provide an ornament at each corner in the form of a star ²⁵ and in the center an ornament in the form of a crescent or moon.

The design is highly ornamental and attractive and may be utilized in other articles of furniture of similar character, such as chiffoniers, washstands, cabinets, hall-racks, &c. ³⁰

Having thus fully described my said invention, what I claim as new, and desire to secure by Letters Patent, is—

The design for a bureau or similar article ³⁵ substantially as herein shown and described.

In witness whereof I have hereunto set my hand and seal, at Washington, District of Columbia, this 24th day of January, A. D. 1902.

MARTIN V. HAMMACK. [L. S.]
